COMBINATION TOOTHBRUSH, CLOSURE CAP AND DENTIFRICE CONTAINER

Arthur A. Gleichert, Mountain Brook, Ala., assignor of a fractional part interest to Lela P. Gleichert

Filed Jan. 4, 1972, Ser. No. 215,447

Term of patent 14 years

Int. Cl. D4—02

U.S. Cl. D4—18

FIG. 1 is a top plan view of a combination toothbrush, closure cap and dentifrice container showing my new design;

FIG. 2 is a side elevational view thereof; and

FIG. 3 is a perspective view thereof, showing the dentifrice container in opened position and the closure cap removed therefrom.

I claim:

The ornamental design for a combination toothbrush, closure cap and dentifrice container, as shown.
